Fred C. Fischer.

F. G. Fischer.

Attorney.

UNITED STATES PATENT OFFICE.

GEORGE A. MALONEY, OF KANSAS CITY, MISSOURI.

TABLEWARE WASHER.

Application filed February 12, 1923. Serial No. 618,506.

To all whom it may concern:

Be it known that I, GEORGE A. MALONEY, a citizen of the United States, residing at Kansas City, in the county of Jackson and 5 State of Missouri, have invented certain new and useful Improvements in Tableware Washers, of which the following is a specification.

My invention relates to a table ware washer, and important features reside in a rockable holder for knives, forks, spoons, etc., and a movable sprinkler which discharges water upon said holder to actuate the same and thoroughly wash the contents thereof, 15 all parts of which latter are exposed to the cleansing action of the water due to the movements of holder and the sprinkler as hereinafter described.

Other features will hereinafter appear, 20 and in order that the invention may be fully understood, reference will now be had to the accompanying drawing, in which:

Fig. 1 is a vertical longitudinal section of a washing machine with the holder 25 mounted therein.

Fig. 2 is a vertical cross section on line II—II of Fig. 1.

Fig. 3 is a detail perspective view of the 30 holder.

Fig. 4 is a plan view of the washing machine tray with the holder mounted therein.

Fig. 5 is a detail vertical section of the 35 holder.

In carrying out the invention, I employ a 40 cabinet 2 which may be similar to the cabinet disclosed in my copending applications, Serial Nos. 487,865 and 618,507, and embraces a door 4 and a lid 6.

8 designates a tray for holding cups, saucers, plates, etc., and is adapted to be placed in and removed from the cabinet 2 through the door 4 and the lid 6.

10 designates the movable holder for knives, forks, spoons, etc., and which as 45 above stated, constitutes an important feature of the invention. Said holder comprises a cup-shaped body portion 12 which is, preferably, cylindrical in form and closed at its bottom and open at its top. The body 50 12 is, preferably, made of wire fabric, so that the refuse washed from the knives, forks, spoons, etc., can pass freely out with the waste water. The body 12 is reinforced with bands 14 and 16, the latter of which 55 is placed intermediate the top and bottom of said body 12 and provided with dia-

trically-opposed vanes 18. A vertical partition 20 divides the body portion 12 into two equal parts to keep the knives, forks, spoons, etc., from shifting about and unbalancing the holder. A shaft 22 extends transversely through the body portion 12 in the same direction as the partition 20 and transversely to the direction in which the vanes 18 extend. The ends of the shaft 22 60 project from opposite portions of the body 12 and are adapted to removably-engage U-shaped bearings 24 secured to the upper portion of the tray 8 at one end thereof. The shaft 22 is spaced below the top of the body 65 12 to permit the same to rock freely as will hereinafter appear, such rocking movement being limited by the vanes 18 contacting stops in the form of transverse rods 25 on the tray 8. Collars 26 fixed to the shaft 22, 70 prevent the same from shifting longitudinally and thus becoming accidentally disengaged from the bearings 24.

28 designates a sprinkler slidably and rockably mounted in bearings 30 fixed in the 75 upper portion of the cabinet 2. The sprinkler 28 may receive its water from a faucet, not shown, through a hose 32 and is provided with one or more sprinkler heads 34. Two sprinkler heads are, preferably, em- 80 ployed, so that while one is discharging water upon the dishes in the tray 8, the other will be discharging water upon the holder 10 to wash the contents thereof and rock said holder to expose all parts of said 85 contents to the cleansing action of the water.

In practice, when the parts are in the positions disclosed by Figs. 1 and 2, water discharged from one of the sprinkler heads 34 90 washes the dishes in the tray 8, while the water discharged from the other sprinkler head washes the contents of the holder 10, as above stated. As the sprinkler 28 is rocked 95 from side to side as indicated by the dotted lines, Fig. 2, the sprinkler head 34 at the right, Fig. 1 washes the dishes in the tray 8, while the companion sprinkler head 34 alternately discharges water against the vanes 18 and thus rocks the holder 10 as indicated by the arcuate arrows Fig. 2, so that all 100 parts of the knives, forks, spoons, etc., within said holder will be subjected to the cleansing action of the water as it sweeps to and fro.

From the foregoing description it will be 110 understood that I have provided means for thoroughly washing all kinds of table ware,

and while I have shown and described the preferred construction, combination and arrangement of parts, I reserve the right to make such changes as properly fall within the spirit and scope of the claims.

Having thus described my invention, what I claim and desire to secure by Letters Patent, is:

1. In a washer of the character described, 10 a vertically-disposed holder, a horizontal shaft fixed to said holder, U-shaped bearings in which said shaft is rockably mounted, and manually-controlled means for alternately discharging a fluid against opposite sides of 15 the holder and the contents thereof to cleanse said contents and actuate the holder.
2. In a washer of the character described, 20 a body for holding articles to be washed, a support on which said body is operably mounted, a pair of oppositely-disposed vanes projecting from said body, and means for alternately discharging a fluid against said vanes to actuate the body and cleanse the articles therein.
3. In a washer of the character described, 25 a rockable body for holding articles to be washed, a partition through said body, a support on which said body is operably mounted, a pair of oppositely-disposed vanes projecting from said body, and a movable sprinkler for alternately discharging a fluid

against said vanes to rock the body and cleanse the articles therein.

4. In a washer of the character described, 35 a cup-shaped body for holding articles and provided with openings, a support on which said body is operably mounted, a pair of oppositely disposed vanes projecting from said body, a rockable sprinkler for alternately discharging a fluid against said vanes 40 to actuate the body and cleanse the articles therein, and a cabinet enclosing the holder and in which said sprinkler is mounted.

5. In a washer of the character described, 45 a rockable body for holding articles and provided with openings, a tray in which said body is operably-mounted, a pair of oppositely disposed vanes projecting from said body, a rockable and longitudinally movable sprinkler for alternately discharging a fluid 50 against said vanes to actuate the body and cleanse the articles therein and in the tray, a cabinet enclosing the holder, the tray and said sprinkler, a tubular bearing in said cabinet and in which said sprinkler is 55 mounted.

In testimony whereof I affix my signature, in the presence of two witnesses.

GEORGE A. MALONEY.
